UNITED STATES PATENT OFFICE.

ERLE H. HAND, OF NEW BRITAIN, CONNECTICUT.

HEIGHT-MEASURING DEVICE.

Application filed August 17, 1925. Serial No. 50,546.

This invention relates to a height measuring device for use in schools, gymnasiums, or in like places, the invention having for an object to provide a simple device of this sort capable of easy manipulation, and which will show the height of the person being measured in inches and fractions and centimeters and fractions thereof.

For further comprehension of the invention, and of the object and advantages thereof, reference will be had to the following description and accompanying drawing, and to the appended claims in which the various novel features of the invention are more particularly set forth.

Fig. 1 of the drawing is a side view showing my improved height measuring device.

Fig. 2 is a face view of the indicator.

Fig. 3 is a horizontal sectional view taken on the line 3—3 of Fig. 2.

Fig. 4 is an enlarged detail vertical sectional view taken on the line 4—4 of Fig. 1.

Fig. 5 is a detail horizontal sectional view showing the braking device, this view being taken on the line 5—5 of Fig. 6.

Fig. 6 is a fragmentary vertical sectional view taken on the line 6—6 of Fig. 5.

In constructing my improved height measuring device I provide an upright casing or housing 10 which may be constructed of wood, metal or suitable material as desired, and which is formed with a tapering top part 10' ending in a diminished neck 11. In this housing a flat bar 12 of less length than the housing is suspended for vertical movement, this bar having on one half of front side scale markings 13 in feet, inches and fractions of inches, and on the other half of front side scale markings 14 in meters, centimeters, and fractions of centimeters. An opening 15 is covered by a window of glass or suitable transparent material 16, is formed in the front of the housing to enable the scale markings on the bar to be seen as they come opposite the indicating marks 17 on the housing or window.

The bar 12 is suspended from a cable 20 which passes out through the neck 11 at the top of the housing in suitable tubing 20' around a pair of pulleys 21, 22 mounted in elbow casings 23 suitably secured to ceiling 10^a and downward from the latter pulley, this cable being connected by a swivel element 24 with a stem 25 on a disk 26 which is adapted to rest on the head of the person being measured. The other end of the cable

has a swivel connection with a shackle 27 mounted on the upper end of the bar 12.

The bar 12 is guided in the housing 10 by means of a number of sets of rollers, there being one set at each corner of the bar, each set comprising a pair of rollers 30 and 31 which engage respectively the front and rear of the housing 10, and another roller 32 which engages the side wall of the housing, these rollers being mounted on suitable brackets 33 fixed to the bar 12 at the corners of the latter.

To cause the bar 10 to remain in the position to which it has been raised, when the plate or disk 26 rests on the head of the person being measured, I may form ratchet teeth 35, 36 on the opposite sides of the bar which are spaced according to the divisions of the respective scales 13 and 14 and which are engaged by pawls 37 fixed on horizontal shafts journaled in the front and rear walls of the casing, these shafts projecting through the front wall of the casing and having handles 38' on their projecting ends, the pawls being urged against the ratchet teeth by means of springs 39.

Fixed on the shafts 38 are gears 42 which mesh with the pinions 43 on other shafts 44 extending below the shafts 38, these having also fixed thereto the cams 45 which are adapted to engage the remote ends of a pair of rods 46 which extend along behind the bar 12 and have adjacent ends connected to an arm 47 which is pivoted as at 48 on the rear wall of the housing and carries a pair of accurately spaced brake elements 49 on its free ends. The rods 46 are guided by means of the apertured member 50 through which the rods extend. The brake arm 47 is held in and returned to neutral position by means of a pair of resilient pins 52 which project from the rear wall of the housing on opposite sides of a pin 53 fixed to the brake arm. When either pawl is moved sufficiently to free it from the bar 12 the corresponding brake element 49 is brought into engagement with the bar and acts to check the descent of the bar. Fixed to the side walls of the casing are spring latches 55 behind which either of the pawls may be engaged to hold it away from the bar. These spring latches 55 are formed by springs 55^a resting on blocks 55^b, and attached to the wall by screws 55^c. When the pawl is moved sufficient distance to engage behind this latch the cam 45 operated in conjunction with the pawl will be

moved beyond the adjacent rod 46 leaving the latter free to move.

To guide the cable over the pulleys in the elbow casings 23 the latter are shown with 5 removable segments 60 in which are quadrant ribs 61 which engage in the enlarged outer portions of the groove in each pulley. The segments 60 may be secured in place by means of bolts 62 passing through retaining 10 lugs or brackets 63 and 64 on the segments and casing bodies respectively.

Having thus described my invention what I claim as new and desire to protect by Letters Patent of the United States is as follows:

- 15 1. In a height measuring device of the class described, a scale-bar having ratchet teeth on a vertical side, a casing housing said scale-bar, means associated with said scale-bar and casing providing for a vertical displacement of said scale-bar, a horizontal shaft journaled in the front and rear walls of said casing, a pawl fixed to said horizontal shaft, and engageable with the said ratchet teeth, means for normally urging 20 said pawl into engagement with said ratchet teeth, a gear fixed on said horizontal shaft, an auxiliary shaft journaled in the front and rear walls of said casing, a pinion fixed to said auxiliary shaft, and meshing with said gear, a cam fixed to said auxiliary shaft, a rod slidably mounted to the rear of said casing, the outer end of said rod being engageable 25 by said cam, an arm pivoted to the rear wall of said casing, and pivotally connected to the inner end of said slidable rod, a brake element fixed to the outer end of said pivoted arm, and engageable with the rear of said scale-bar, and resilient pins projecting 30 from the rear wall of said casing, and normally disengaging brake element from said scale-bar, whereby by disengaging said pawl from the said ratchet teeth, the said brake element engages said scale-bar.
- 35 2. In a height measuring device of the class described, a scale-bar having ratchet teeth on a vertical side, a casing housing said scale-bar, means associated with said scale-bar and casing providing for a vertical displacement of said scale-bar, a horizontal shaft journaled in the front and rear walls of said casing, a pawl fixed to said horizontal shaft, and engageable with the said ratchet teeth, means for normally urging 40 said pawl into engagement with said ratchet teeth, a gear fixed on said horizontal shaft, an auxiliary shaft journaled in the front and rear walls of said casing, a pinion fixed to said auxiliary shaft, and meshing with said gear, a cam fixed to said auxiliary shaft, a rod slidably mounted to the rear of said casing, the outer end of said rod being engageable by said cam, an arm pivoted to the rear wall of said casing, and pivotally connected to the inner end of said slidable rod, a brake element fixed to the outer end of said pivoted arm, and engageable with the rear of said scale-bar, and resilient pins projecting from the rear wall of said casing, and normally disengaging brake element from said scale-bar, whereby by disengaging said pawl from the said ratchet teeth, the said brake element engages said scale-bar.

normally disengaging brake element from said scale-bar, whereby by disengaging said pawl from the said ratchet teeth, the said brake element engages said scale-bar.

2. In a height measuring device of the class described, a scale-bar having ratchet teeth on a vertical side, a casing housing said scale-bar, means associated with said scale-bar and casing providing for a vertical displacement of said scale-bar, a horizontal shaft journaled in the front and rear walls of said casing and having an end projecting through the front wall of said casing, an operating handle fixed to said projecting end, a pawl fixed to said horizontal shaft, and engageable with the said ratchet teeth, means for normally urging said pawl into engagement with said ratchet teeth, a gear fixed on said horizontal shaft, an auxiliary shaft journaled in the front and rear walls of said casing, a pinion fixed to said auxiliary shaft, and meshing with said gear, a cam fixed to said auxiliary shaft, a rod slidably mounted to the rear of said casing, the outer end of said rod being engageable by said cam, an arm pivoted to the rear wall of said casing, and pivotally connected to the inner end of said slidable rod, a brake element fixed to the outer end of said pivoted arm, and engageable with the rear of said scale-bar, and resilient pins projecting from the rear wall of said casing, and normally disengaging brake element from said scale-bar, whereby by disengaging said pawl from the said ratchet teeth, the said brake element engages said scale-bar.

In testimony whereof I have affixed my signature.

ERLE H. HAND.
